UNITED STATES PATENT OFFICE

168,523

BOTTLE

Charles M. Sittason, Cincinnati, Ohio, assignor to The Andrew Jergens Company, Cincinnati,
 Ohio, a corporation of Ohio

Application October 17, 1952, Serial No. 21,866

Term of patent 7 years

(Cl. D58—6)

To all whom it may concern:

Be it known that I, Charles M. Sittason, a citizen of the United States, residing at Hamilton County at Cincinnati, Ohio, have invented a new, original, and ornamental Design for a Bottle, of which the following is a specification reference being had to the accompanying drawing, forming a part thereof.

I claim:

The ornamental design for a bottle, substantially as shown.

CHARLES M. SITTASON.
